US00D804235S

(12) **United States Design Patent** (10) **Patent No.:** **US D804,235 S**
(45) **Date of Patent:** **** Dec. 5, 2017**

(54) **STEAMER BASKET**

(71) Applicant: **CNA International Inc.**, Wood Dale, IL (US)
(72) Inventors: **Kristin Marie Affatato**, Elmhurst, IL (US); **Steve Cho**, Chicago, IL (US); **Hyunchul Kim**, Chicago, IL (US); **Michael Prince**, Chicago, IL (US)

(73) Assignee: **CNA International Inc.**, Wood Dale, IL (US)

(**) Term: **15 Years**

(21) Appl. No.: **29/572,918**

(22) Filed: **Aug. 1, 2016**

(51) **LOC (10) Cl.** **07-02**

(52) **U.S. Cl.**

USPC **D7/354**

(57) **CLAIM**

We claim the ornamental design for a steamer basket, as shown and described.

DESCRIPTION

FIG. 1 is a top front perspective view of a steamer basket according to the new design.

FIG. 2 is a bottom side perspective view of the steamer basket shown in FIG. 1.

FIG. 3 is a right side view of the steamer basket shown in FIG. 1.

FIG. 4 is a left side view of the steamer basket shown in FIG. 1.

FIG. 5 is a front view of the steamer basket shown in FIG. 1.

FIG. 6 is a back view of the steamer basket shown in FIG. 1.

FIG. 7 is a top view of the steamer basket shown in FIG. 1; and,

FIG. 8 is a bottom view of the steamer basket shown in FIG. 1.

1 Claim, 6 Drawing Sheets
